2 SHEETS—SHEET 2.

UNITED STATES PATENT OFFICE.

THEODORIC TAYLOR, OF PARKERSBURG, WEST VIRGINIA, AND WILLIAM M. STUART, OF MOUNT OLIVER BOROUGH, PENNSYLVANIA.

INVALID-BED.

No. 926,033.

Specification of Letters Patent.

Patented June 22, 1909.

Application filed February 6, 1909. Serial No. 476,518.

To all whom it may concern:

Be it known that we, THEODORIC TAYLOR and WILLIAM M. STUART, citizens of the United States of America, residing at (1) Parkersburg, (2) Mount Oliver borough, in the county of (1) Wood, (2) Allegheny, and State of (1) West Virginia, (2) Pennsylvania, have invented certain new and useful Improvements in Invalid-Beds, of which the following is a specification, reference being had therein to the accompanying drawing.

This invention relates to invalid beds, and the primary object of our invention is the provision of novel means in connection with a bed for elevating the head or feet of a patient, whereby the patient can be retained in a comfortable position or in a position conducive to the curing of certain ailments.

Another object of our invention is to provide an attachment for an ordinary metallic bed that will permit of a patient being positioned whereby bed pans can be used without disturbing the comfort of the patient.

A further object of our invention is to provide an attachment for beds that can be advantageously used in hospitals for correctly positioning a patient, whereby a surgical operation can be made, limb fractures properly taken care of, and the comfort of a person upon the attachment made perfect.

A still further object of our invention is to provide an adjustable support that can be easily and quickly attached to a bed and manipulated to support a person in a comfortable position, whether the same is used in a sick room or simply for lounging purposes.

With the above and other objects in view which will more readily appear as the invention is better understood, the same consists in the novel construction, combination and arrangement of parts to be hereinafter described and then specifically claimed.

Referring to the drawings:—Figure 1 is an elevation of a bed equipped with our attachment, Fig. 2 is an end view of the same, and Fig. 3 is a cross sectional view of a bed and its attachment.

In the accompanying drawings, we have illustrated a metallic bed having head and foot pieces, the head piece comprising cylindrical posts 1 and the foot piece cylindrical posts 2, the posts of the foot piece

being connected to the posts of the head piece by longitudinally disposed rails 3. 55

Clamped to the posts 1 of the head piece and at the upper ends thereof are sleeves 4 provided with parallel flanges 5. Journaled in the flanges 5 is a transverse shaft 6 having one end thereof provided with a ratchet wheel 7 and a crank 8. Adapted to engage the ratchet wheel 7 and prevent a rearward rotation of said wheel and the shaft 6 is a pivoted gravity pawl 9, said pawl being carried by the flanges 5 adjacent to the wheel 7. Fixed to the shaft 6 and adapted to wind thereon are cables 10, said cables being connected to a transverse bar 11 fixed to sleeves 12 slidably mounted upon the posts 1. The foot piece of the bed is similarly equipped, with the exception that the shaft 6 is provided with loose grooved sheaves or pulleys 13, these loose sheaves or pulleys being employed for supporting a rope or cable used for maintaining a fractured limb in a free and easy elevated position.

The sleeves 12 of the head and foot pieces of the bed are provided upon the inner edges thereof with pivoted links 14 and pivotally connected to said links are two frames 15 and 16 approximately the area of the bed, said frames having the confronting ends thereof pivotally connected together, as at 17. The frames 15 and 16 are adapted to support strips of fabric or sheeting 17 having suitable openings formed therein, whereby easy access can be had to the under side of the body lying upon the attachment. To add rigidity to the frames 15 and 16, a yoke 18 is used for connecting the sides of the frames 15 adjacent to the inner pivoted end of said frame.

To maintain the frames 15 and 16 in a horizontal plane, the sides of the frame 15 are provided with pivoted links 19 having notches 20 for receiving pins 21 carried by the sides of the frame 16. In order that the links 19 can be supported in connection with the frame 15, said links are provided with notches 22 to receive pins 23, carried by the sides of the frame 15.

To prevent the inner pivoted ends of the frames 15 and 16 from sagging due to the weight of a body upon the same, the longitudinal rails 3 of the bed are provided with

pivoted members 24, said members being slotted and adjustably connected to supports 25 having extensions 26 for supporting the inner pivoted ends of the frames 15 and 16.

5 The supports 25 are connected to the members 24 by wing thumb nuts 27 and by adjusting said wing thumb nuts, the supports 25 can be positioned to properly support the pivoted ends of the frames 15 and 16. The 10 projections 26 of the supports 25 are adapted to engage the rails 3, as shown in dotted lines in Fig. 1, and support the members 24 when not in use.

The outer ends of the frames 15 and 16 15 can be easily elevated by rotating the cranks 8 to either support the head or feet of a body at a greater elevation than the central portion of a body. By maintaining the links 19 in the position shown in Fig. 1, the 20 frames 15 and 16 can be elevated a considerable distance above the rails 3 and the supports 25 adjusted to prevent the inner pivoted ends of the frames 15 and 16 from sagging.

Our attachment in its entirety is made of 25 a light and durable non-corrosive material and the simplicity of construction permits of the present type of hospital bed being equipped with the attachment at a comparatively small cost.

30 While in the drawings forming a part of this application there is illustrated the preferred embodiments of our invention, we would have it understood that the detail construction thereof can be varied or changed as 35 to shape, proportion and manner of assemblage without departing from the spirit of the invention.

Having now described our invention what we claim as new, is:—

40 1. In an invalid bed, the combination with a bed having head and foot pieces, and rails connecting said head and foot pieces, of sleeves fixed upon said head and foot pieces, shafts revolvably supported by said sleeves, cranks 45 mounted upon said shafts, cables connecting with said shafts and adapted to wind thereon, bars connected to the lower ends of said cables, sleeves slidably mounted upon the head and foot pieces of said bed and connecting with said bars, pivoted links supported by said sleeves, frames pivotally supported by said links and having the ends thereof connected together, links pivotally carried by one of said frames and adapted 50 to engage the other of said frames for maintaining a rigid connection between said frames, adjustable supports carried by the rails of said bed for engaging the pivoted ends of said frames and preventing said

frames from sagging, and means supported 60 by the first mentioned sleeves for preventing a rearward rotation of said shafts.

2. In an invalid bed, the combination with head and foot pieces, the rails connecting said head and foot pieces, of sleeves fixed 65 upon said head and foot pieces, shafts revolvably supported by said sleeves, sleeves adjustably mounted upon said head and foot pieces and adapted to be moved by a rotation of said shafts, links pivotally carried by said slidable sleeves, frames pivotally connected to said links and adapted to be pivotally connected together, a depending yoke carried by one of said frames, links carried by one of said frames and adapted to 70 engage the other of said frames for providing a rigid connection between said frames, and adjustable supports carried by said rails for engaging said frames and preventing the pivoted ends thereof from sagging.

3. In an invalid bed, the combination with head and foot pieces, and rails connecting said head and foot pieces, of sleeves fixed 85 upon said head and foot pieces, shafts revolvably supported by said sleeves, sleeves adjustably mounted upon said head and foot pieces and adapted to be moved by a rotation of said shafts, links pivotally carried by said slidable sleeves, frames pivotally connected to said links and adapted to be pivotally connected together, links carried by one of said frames and adapted to engage the other of said frames for providing a rigid connection between said frames, and adjustable supports carried by said rails for 90 engaging said frames and preventing the pivoted ends thereof from sagging.

4. In an invalid bed, the combination with a bed having head and foot pieces, and rails connecting said head and foot pieces, of sleeves fixed upon said head and foot pieces, shafts revolvably supported by said sleeves, sleeves slidably mounted upon said head and foot pieces and adapted to be moved by a rotation of said shaft, links pivotally connected to said slidable sleeves, frames pivotally connected to said links and adapted to be pivotally connected together, and adjustable supports carried by said rails for 100 engaging the pivoted ends of said frames and preventing said frames from sagging.

105 In testimony whereof we affix our signatures in the presence of two witnesses.

THEODORIC TAYLOR.
WILLIAM M. STUART.
